His ATTORNEY

UNITED STATES PATENT OFFICE

105,703

DESIGN FOR A PISTOL GRIP LAMP

Robert H. Hummert, Dayton, Ohio, assignor to
The S. H. Thomson Manufacturing Company,
Dayton, Ohio, a corporation of Ohio

Application December 16, 1936, Serial No. 66,573

Term of patent 14 years

To all whom it may concern:

Be it known that I, Robert H. Hummert, a citizen of the United States, residing in the city of Dayton, in the county of Montgomery and State of Ohio, have invented a new, original, and ornamental Design for a Pistol Grip Lamp, of which the following is a specification, reference being had to the accompanying drawing, forming part thereof.

The figure is a perspective view of a pistol grip lamp, showing my new design.

I claim:

The ornamental design for a pistol grip lamp, as shown.

ROBERT H. HUMMERT.
